(62) Division of application No. 29/214,446, filed on Oct. 1, 2004.

Primary Examiner—Robert M. Spear

Assistant Examiner—Katrina A. Kile

(74) *Attorney, Agent, or Firm*—Price, Heneveld, Cooper, DeWitt & Litton LLP

(30) **Foreign Application Priority Data**

(57) **CLAIM**

Jun. 7, 2004 (FR) 191457

We claim the ornamental design for a chair, as shown and described.

(51) **LOC (8) Cl.** **06-01**

DESCRIPTION

(52) **U.S. Cl.** **D6/375; D6/366**

This application incorporates by reference essential material from parent application 29/214,446. All of the material from the parent application that is essential to the claimed design is included herein. Any material in the parent application which is not present herein forms no part of the claimed design.

(58) **Field of Classification Search** D6/375, D6/334, 502, 498, 499, 366, 364-365; 297/411.27, 297/452.29, 451.4, 451.5, 451.6, 452.14, 297/448.2

FIG. 1 is a front perspective view of a chair showing our new design;

See application file for complete search history.
